UNITED STATES PATENT OFFICE.

ALFRED U. DAVIS, OF BALTIMORE, MARYLAND, ASSIGNOR TO DAVIS INSTRUMENT MANUFACTURING COMPANY, INCORPORATED, A CORPORATION OF MARYLAND.

BLAST MAGNETO.

Application filed November 8, 1926. Serial No. 147,097.

This invention relates to improvements in blast magnetos, and has for its object to provide a simple and efficient device for generating a current of electricity to be carried 5 to any desired point for the purpose of firing a blast.

The invention consists of the novel construction and arrangement of the parts and combination of parts hereinafter more fully 10 set forth in the following specification and pointed out in detail in the appended claim.

In the accompanying drawings,—

Figure 1 is a side elevation of my invention.

15 Figure 2 is a similar view to Figure 1 the casing being in the vertical section.

Figure 3 is a detail elevation of the parts removable from the casing showing the opposite side from that shown in Figure 2.

20 Figure 4 is a section on the line 2—2 of Figure 3.

Figure 5 is a detail side view of the armature.

25 Figure 6 is a detail view of the armature showing the contact plates in section.

Referring to the accompanying drawings, forming part of this specification, and in which like reference numerals designate like parts throughout the several views thereof, 1 30 designates the outer casing having a removable cover 2 and binding posts 3 and 4. Between the binding posts 3 and 4 and the cover 2 is an insulating piece 5. The binding post 3 is insulated from the cover 2 by means of the insulating piece 5 and the insulating disk 6. The binding post 4 is grounded to the cover 2. Within the casing 1 is a laminated magnet 7 composed of a 35 number of plates, held together by the sleeve 8 and the retaining plate 9 which latter is held in position by the pin 10. Mounted in the sleeve 8 is a segment gear 11 having a recess in its face across which the key pin 12 projects. The shaft of the segment gear 40 11 which projects in to the sleeve 8 is provided with a coiled spring 13 to hold the said segment gear in its normal position.

The said segment gear 11 is in mesh with the pinion 14 rigidly fixed to the shaft 15. 45 The said shaft 15 is mounted in the bearing 16 and is provided on its opposite end with a gear wheel 17 which latter is in mesh with the pinion 18 on the shaft 19 of the armature. The said armature is composed of the 50 core 20 secured to the plates 21 and 22 and

wound with the wire 23. The plate 21 carries a pawl 24 pivoted at one end thereto and having its free end co-operating with the ratchet 25 just back of and carried with the pinion 18. The plates 21 and 22 are 55 provided with the shafts 19 and 26 respectively, which are mounted in the bearing plates 27 and 28 and revolve therein. One end of the wire 23 is grounded on the core 20 and the other end is secured to a metal 60 disk 29 which is insulated from the plate 22 by the washer 30. The said metal disk 29 is provided with an aperture through which the shaft 26 projects. The contact plate 31 is in constant contact with the metal 65 disk 29 and is insulated from the bearing plate 28 by the insulation washer 32. The said contact plate 31 has a wire 33 connected thereto at one end and its opposite end secured to the pin 34 having a nut 35 to hold the wire in position on said pin. Said pin projects through the magnet plates 7 and is insulated therefrom. To the opposite end of the pin 34 is secured the contact plate 36 70 which is also insulated from the magnet 75 plates and has its upper end in constant contact with the binding post 3. Projecting through the upper end of the magnet 7 is a stop 37 to limit the movement of the segment gear 11.

When the device is to be operated the wires leading to the charge to be fired are connected to the binding posts 3 and 4. The key is then inserted in the casing 1 across the pin 12. A quick turn of the key will 80 90 revolve the segment gear 11, cause the shaft 15 to revolve, which in turn through the mechanism described causes the armature to be rapidly revolved and thereby generate current which is then carried off through the disk 29 and contact plate 31 through the wire 33 and contact plate 36 to the binding post 3 and through the wires connected to the binding posts 3 and 4 to the charge to be fired.

Having thus described my invention what I claim is:

A blast magneto comprising a casing, a magnet secured within said casing, binding post at one end of said casing, an armature 105 revolvably mounted in said casing, a contact disk secured to one side of said armature and insulated therefrom and having one end of the armature wire connected thereto, a contact plate in constant contact with said 110

disk and connected with one of said binding posts, a pinion on one end of the armature shaft, a gear in mesh with said pinion, a pinion shaft on which said gear is mounted, a pinion on opposite end of said last mentioned shaft, a sleeve to which the magnet plates are secured, a segment gear mounted in said sleeve and in mesh with the last mentioned

pinion, and having a recess in one side thereof, a pin projecting across said recess of said segment gear and means co-operating with said pin for turning the segment gear and revolving the said armature. ¹⁰

In testimony whereof I affix my signature.

ALFRED U. DAVIS.
